(57) **CLAIM**

The ornamental design for a container for stick fragrance diffusers, as shown and described.

DESCRIPTION

FIG. 1 is a perspective view of a container for stick fragrance diffusers showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view; the sticks are shown in dashed lines for illustrative purposes only and form no part of the present invention.

The broken lines in the drawings are for illustrative purposes only and form no part of the claimed design.
